SUPPORTING HEAD FOR ABRASIVE DISKS

William Stever, Philadelphia, Pa., assignor to Edward G. Budd Manufacturing Company, Philadelphia, Pa., a corporation of Pennsylvania

Application September 15, 1943, Serial No. 502,422

2 Claims. (Cl. 51—197)

1

The invention relates to supporting heads for polishing disks such as there are used for grinding off or polishing the surfaces of sheet metal stampings prior to painting.

Among the objects of the invention is a head which permits the easy attachment or removal of the abrasive disk, an object of greatest importance because such disks wear out rather rapidly and a great number of them are used by one workman in the course of one working day.

Another object of the invention is a head for an abrasive disk which has no sharp projecting parts liable to cause injury to the workman or mar the workpiece to be polished.

A still further object of the invention is a supporting head of the indicated type which holds the abrasive disc so firmly that there is no danger of the disk getting loose and causing injury by being whirled around in the shop.

An object of the invention is also means for the attachment of a plate or pad supporting the abrasive disk in such a manner that this plate can likewise easily be exchanged and is nevertheless held securely in place.

The above and other objects of the invention are achieved by the formations of the head and of the portions of the disk and the backing plate which are shown in the attached drawings and described in the following.

In the drawings:

Fig. 1 is a fragmentary plan view of an abrasive disk and its supporting head, certain portions being broken away for the purpose of showing the interior construction.

Fig. 2 is a section along line 2-2 of Fig. 1.

Fig. 3 is a fragmentary rear view of an abrasive disk and of the member for holding it.

Fig. 4 is a section along line 4-4 of Fig. 3.

Fig. 5 is a view similar to Fig. 1 but of a modified form of the invention.

Fig. 6 is a section along line 6-6 of Fig. 5.

Fig. 7 is a plan view of the supporting head shown in Figs. 5 and 6.

Fig. 8 is an exploded perspective view of the supporting head, the backing pad and the abrasive disk with its holder of a third embodiment of the invention.

Fig. 9 is a fragmentary plan view partly in section of the construction shown in Fig. 8.

Fig. 10 is a section mainly along line 10-10 but partly along line 10'-10' of Fig. 9.

The supporting head illustrated in Figs. 1 and 2 consists mainly of three concentric members 11, 12 and 13 which are screw threaded into one another. The driving shaft 14 is screw threaded

2

into the central member 11 and connected such as by a flexible shaft to a driving motor (not shown). Members 12 and 13 are secured in their relative positions by a set screw 15.

5 Member 13 has a marginal plane portion 16 and a central recessed conical portion 17. The member 12 projects beyond the central portion of member 14 and is provided with short cylindrical ribs 18 which carry radially extending ribs 19 and 20. Pins 21 project inwardly from one end of each of the ribs 19, 20. There are three ribs 18 with wings 19, 20; each of these structures extends over less than $\frac{1}{6}$ of the circumference leaving a somewhat wider space between them.

15 The circular metal plate 22 is shaped corresponding to the shape of the surfaces 16, 17, but extends outwardly beyond it. The outwardly extending portion is secured by rivets 23 to a flexible disk 24 which may consist of fiber, metal, or
20 any other suitable material. The disk 24 extends inwardly beyond the rivets 23 but is slightly spaced from the inner portion of the disk 22.

At its inner circumference the disc 22 is provided with radially inwardly projecting portions 25 which are adapted to enter between to be turned under the extensions 19 into the position illustrated in Figs. 1 and 2. The rotation of the portions 25 is limited by the aforesaid pins 21.

30 The detachable central member 26 has radially outwardly projecting segments 27 near its one end which are adapted to enter between the extensions 28 and to engage the latter by turning movement. Here again the movement is limited by the pins 21. The outer portion of the member 35 26 has a radially flaring portion 28 with a flat outer surface 29 and a shallow conical surface 30. The latter has two radial substantially square extensions 31 which fit into corresponding recesses of the abrasive disk 32. The abrasive disk 40 may have radial slots 33 which adapted them for use with other known types of heads.

45 For removing the abrasive disk 32, it is simply turned counter-clockwise. The disk takes the central holding member 26 along and brings it out of engagement with the extensions 20 of the member 12. For inserting a new disk, the member 26 is put in place on the central portion of the disk, then pushed into the head and given a slight twist so that its projections 27 grip under the extensions 20 of the member 12. The rotation of the shaft 14 should, of course, be opposite to the direction necessary for bringing the member 26 or the plate 22 into place. The exchange of the disk or plate 22 in case it should 50 be worn out or the substitution of a disk of dif-

ferent flexibility as desired, is just as easy as and corresponds to the exchange of the abrasive disk 33.

It will be noted that the new device has no projecting parts, that the abrasive disk is firmly held between the member 26 and the inwardly flaring portion of the backing disk 24, and that the entire head is light and compact, does not require great amounts of valuable metal and can, due to its light weight, easily be operated without causing undue fatigue of the workman.

In the embodiment shown in Figs. 5, 6 and 7, there is again a driving shaft 34 and a head composed of three members 35, 36 and 37 screw threaded into one another. There is, furthermore, just as in a preceding embodiment, a plate 40 attached to a backing plate or pad 41 and releasably engaged with the member 36 by inward projections 38 which engage outward projections 39 closed at one end by a pin 40'. The holding member for the abrasive disc 41 consists in this embodiment of a nut 42 having an outwardly extending plate 43 which presses the inner portion of the disk 44 and the pad 41 against plate 40. This construction affords a firmer grip of the abrasive disk, but it requires slightly more time to exchange a disk because the member 42 has to be rotated several times as compared with the short movement required for the corresponding member 26 of the first embodiment.

The embodiment shown in Figs. 8, 9 and 10 is quite similar to the embodiment shown in Figs. 1 to 4, indeed, so similar that the same reference numerals are used for the corresponding parts and so that attention may be directed to the description of the first embodiment. The illustration of this last embodiment will also make the construction to the embodiment shown in Figs. 1 to 3 more easily understood. The outstanding difference consists in the details illustrated in Figs. 9 and 10. The extension 28 of the member 12 and the projection 27 are both slightly offset at 45 so that the portion of the extension 28 remote from the pin 21 is slightly thicker and the portion of the projection 27 close to the pin 21 is slightly thicker than the respective remaining portion. The amount of this offset is exaggerated in Fig. 10. Its purpose is to hold the two members firmly together by letting the thickened portion of the projection 37 enter behind the thinner portion of the extension 28. Yet, the

amount of this offset is so small that it does not prevent the disengagement between the members if sufficient force is applied.

The invention is not restricted to the illustrated embodiments but is liable to such modifications as will occur to those skilled in the art. All such modifications are intended to be covered by the attached claims.

What is claimed is:

1. Head for holding abrasive disks comprising a flat body of rotation adapted on one side for attachment to a driven shaft and having its opposite side concentrically recessed; concentric rib formed projections integral with said body extending into the recess from the bottom thereof; radial outward and inward sector shaped integral extensions on said projections; a holding plate for a backing pad engaging the outward extensions with mating radially inwardly directed extensions on the margin of a central opening in the plate; a holding member for an abrasive disk engaging said inward extensions with mating extensions formed on the outside of a cylindrical portion of said holding member; the arrangement being such that said holding plate and said holding member upon rotation relative to said body may be disengaged from and reengaged with said body.

2. Head for holding abrasive disks comprising a cylindrical body of rotation adapted on one side for the connection with a driven shaft while its opposite side is provided with a recess and integrally with supporting means arranged concentrically to the axis of rotation and projecting into the recess from the bottom thereof; radially outwardly extending sector shaped extensions on and integral with said means and arranged in the recess spaced from the bottom thereof; a backing pad and a holding plate therefor, said plate having a portion fitting into said recess and provided with radially inwardly directed sector shaped extensions on the margin of a central opening in the plate; said plate engaging the recessed side of said body and with its extensions the extensions of the body so that upon relative rotation said body and plate may be disengaged and reengaged; and a holder member for an abrasive disk releasably engaging said body radially inwardly of said means.

WILLIAM STEVER.
